UNITED STATES PATENT OFFICE.

RAY V. GRIGGS, OF CHICAGO, ILLINOIS.

DESIGN FOR A BRACKET FOR TELEPHONE-STANDS.

SPECIFICATION forming part of Design No. 34,084, dated February 12, 1901.

Application filed November 5, 1900. Serial No. 35,578. Term of patent 7 years.

To all whom it may concern:

Be it known that I, RAY V. GRIGGS, a citizen of the United States, residing at Chicago, in the county of Cook and State of Illinois, have invented a certain new and original Design for a Bracket for Telephone-Stands, (Case No. 1,) of which the following is a full, clear, concise, and exact description, reference being had to the accompanying drawings, forming a part of this specification.

The object of my invention is to provide a simple and advantageous design for a bracket for supporting telephone-stands.

In the accompanying drawings I have shown my bracket.

In the drawings, Figure 1 is a side view of the bracket, and Fig. 2 a top view thereof.

Like parts are indicated by similar characters of reference in both views.

My bracket comprises a supporting portion ²⁰ a, provided with longitudinal extensions or arms b b. A horizontal arm e is secured by means of two longitudinally-extending arms to the member a by the pintle f. A circular plate g is secured to the arm e by means of ²⁵ a vertical extension of the said arm.

What I claim as my invention is—

The design for a bracket for supporting telephone-stands, substantially as herein shown and described. ³⁰

In witness whereof I hereunto subscribe my name this 3d day of November, A. D. 1900.

RAY V. GRIGGS.
